United States Patent Office

Des. 192,699
Patented May 1, 1962

192,699

FLOW METER

Ellis E. Charles, Kansas City, Mo., assignor to W. E. Anderson, Inc., Kansas City, Mo., a corporation of Missouri

Filed Aug. 21, 1961, Ser. No. 66,441

Term of patent 14 years

(Cl. D52—6)

Fig. 1.

Fig. 4.

Fig. 2.

Fig. 5.

Fig. 3.

FIG. 1 is a front elevational view of a flow meter, showing my new design.

FIG. 2 is a top plan view thereof;

FIG. 3 is a bottom view thereof;

FIG. 4 is a side elevational view thereof; and

FIG. 5 is a rear elevational view of a flow meter.

The undisclosed side of the flow meter is substantially the same in appearance as the side shown.

I claim:

The ornamental design for a flow meter, as shown and described.
